Specification of Letters Patent.

Patented Mar. 3, 1914.

Original application filed October 30, 1905, Serial No. 285,045. Divided and this application filed August 11, 1910. Serial No. 576,616.

To all whom it may concern:

Be it known that I, JAMES H. DEAN, a citizen of the United States, and a resident of Chicago, county of Cook, and State of Illinois, have invented certain new and useful Improvements in Voting-Machines, of which the following is a specification.

The improvement relates to voting machines and seeks to provide a suitable construction which is provided with both ordinary and straight ticket keys, and in which provision is made for casting irregular ballots.

A further object of the invention is to provide a machine which cannot be improperly manipulated.

The invention consists in the features of construction, combinations and arrangements of parts hereinafter set forth, illustrated in the accompanying drawings and more particularly pointed out in the appended claims.

The machine in which these inventions are embodied is more fully illustrated in my application No. 285,045 of which this application is a division. Application 285,045 is now Patent 972,513, issued October 11, 1910.

In the drawings Figure 1 is a longitudinal section of the upper portion of the machine. Fig. 2 is a plan view of one of the unit frames or sections showing the interlocking mechanism. Fig. 3 is a rear view of the machine with the back cover-plate removed. Fig. 4 is a view partially in section of the end portion of one of the machine units. Figs. 5 and 6 are detail sections respectively on lines 5—5 and 6—6 of Fig. 4. Fig. 7 is an end view of the machine with parts shown in section. Fig. 8 is a view of the ribbon-holder employed as part of the free ballot mechanism. Fig. 9 is a detail view of one of the grouping interlocking blocks.

The machine shown in the drawings, like that set forth in my prior Patent No. 636,730 of November 7, 1899, is made up of units or sections, each unit having counters for all of the candidates for a given office. It is to be understood however that numerous features of the present invention are not dependent on the sectional or unit feature and may be applied to machines of other types.

The machine comprises a base section and a top section, with as many units interposed as are required for the number of offices to be filled at an election. The units each containing a group of counters for a single candidate are thus arranged in horizontal rows while the party tickets are arranged in vertical rows.

The frame of the machine is preferably formed of sheet metal and comprises the base frame 1, the unit or section frames 2, the amendment sections 3, the straight ticket section 4 and the top section 5, together with a sheet metal back plate 6. The sections or unit frames may be held together in any suitable way, as by means of through bolts 7. Preferably also, the sections are provided with interlocking tongues and notches 8 and 9, as indicated. The machine as a whole is carried at a suitable height above the floor upon legs or supports 10, the upper portions only of which are shown in the drawings.

A short shaft 11 is journaled in vertical position upon the upper, central portion of the top frame 5 and a supporting arm 12 is centrally fixed to the upper projecting end of the shaft. The ends of the support or arm 12, extend beyond the ends of the machine and carries a laterally extending bow shaped rod from which hangs a curtain that forms the booth for the machine. The arm 12 is provided with depending handles by which the booth may be rotated around the machine to alternately inclose and expose the face of the machine which carries the voting keys. The short shaft 11 extends through the cover plate of the top section 5 and it is journaled at its lower end in its bracket 16, that is held in place by bolts 17, below the top of the upper section 5 and, in the bracket 16, are arranged a ratchet wheel 18 and a sprocket 19 which are fixed to the shaft 11. A spring-held pawl 20 swiveled on one of the bolts 17, engages the teeth of the ratchet 18 and prevents the rotation of the shaft 11 and booth connected thereto in one direction.

A sprocket wheel journaled on a stud 22 at one end of the top section 5, is connected to the sprocket 19 by a chain 23. The lower face of the sprocket 21 is provided with a shoulder or key 24, which is adapted to fit

a corresponding key-way formed in a crown piece 25 upon the upper end of the motor shaft 26. This shaft 26 is square as shown, and extends through all of the units or sections of the machine. Within each unit section is arranged a sleeve 27 having a square hole to fit the motor shaft and each sleeve has an upper, lower and central flange as shown, forming grooves 28 within which are set the tappet pins 29 and 30.

The central unit frames or sections are preferably channel or trough-like, that is to say, the bottoms of the sections are closed and their tops opened. On the bottom of each section is arranged to slide a bar 31 for operating the counter actuators of that section. At the top of the unit is arranged a longitudinally extending restoring bar 32 for locking the voting keys and for restoring them to normal position. At the end of the unit frame each of these bars is provided with a square head 33 which snugly fits between the front and back portions thereof and which is provided upon one side with a hook 34 and on its opposite side with a shoulder 34' similar to that shewn at left end of Fig. 2 in connection with the bar 31. The tappet pins 29 and 30 upon the motor sleeve 27, coöperate with the hooks 34 and shoulders 34' to shift the actuating bar and restoring bar back and forth. The motor shaft rotates in the direction of the arrow and it should be noted, that the tappet pin 29 for operating the actuator bar, is in advance of the pin 30, which operates the restoring bar.

Each of the office sections or units is preferably provided with six or seven counters or registers. Each of the counters is provided with three dials 35 and each dial has ten figures which show through openings in the front plate of the unit frame as shown in Fig. 2 of Patent 972,513. Each dial is attached to a sleeve 37 carrying gears by which one revolution of the unit dial is connected to the tens dial so as to advance it one step and in like manner advance the hundreds dial when the tens dial has completed a revolution. The units and tens sleeves are provided with single actuator teeth 38 which coöperate with intermittent gears 39 on the tens and hundreds sleeves respectively. The tens and hundreds sleeves are provided with locking wheels 40 which coöperate with cylindrical surfaces 41 upon the tens and units sleeves respectively, and these surfaces are mutilated at points opposite the actuator teeth 38 so as to free the corresponding locking wheel 40 when the corresponding actuator tooth 38 is in engagement with the gear 39. This particular arrangement of operating gearing for the counter dials is set forth in prior application filed by me No. 742,031 December 30, 1899, and need not be more fully described here.

The units and hundreds sleeves 37 are mounted upon the forward reduced ends of cross studs 42 while the tens sleeve is mounted upon the forward ends of the cross studs 43, which are reduced at their extreme forward ends (see Fig. 4). These studs are free to turn and are held in place by pins which are driven through the same just inside of the back plate of the unit frame after the studs are inserted. The stud 42 upon which the unit sleeve is placed is provided with a square part or key 44 upon which the unit sleeves 37 fit. The end of this stud projects beyond the end of the face of the frame and is made square to receive a crank or tool by which the counter wheels, when released from their actuator, may be returned to zero. The several voting keys 45 extend through openings in the front of the unit frame and the rear ends are connected to U-shaped slides 46, each of which is freely mounted upon two of the pins 42.

The key-locking and restoring bar 32 (see Figs. 4 and 5) is provided with shoulders or lugs 56 on its front edge which coöperate with pins 57 to normally hold the keys 45 in locked position. Pins 57 extend through the slides 46 as shown, just behind the rear ends of the keys. As the voter approaches the machine and the booth is turned to inclose its face, as is shown in Patent No. 972,513, the pin 30 will engage the hook 34 and shift the restoring bar to move the lugs 56 away from pins 57, so that the keys may be moved to set the corresponding actuators. As the voter retreats from the machine, the tappet 30 coöperates with the shoulder 34' to shift the restoring bar to the opposite direction and the cam-faces 58 of the lugs 56 engage the pins 57 on the slides and force the keys and actuators back to normal locked position.

It should be noted that the movement of the motor shaft 26 is always in the same direction inasmuch as the centrally mounted booth always revolves in one direction and can only revolve in one direction about the machine. The actuator bar tappet 29 in advance of the restoring bar tappet 30 insures that the actuator bar will be operated first both when the voter advances to and when he retreats from the machine. If the restoring or locking bar were operated first as the voter approaches the machine, he could then push in one or more of the keys and actuators before the actuator-bar was shifted, so that, when this did occur, one or more of the counters would be moved back one number. Of course, the actuator-bar must be operated before the restoring bar as the voter leaves the machine, for otherwise the counters would not properly register the ballot cast.

The limiting mechanism for preventing the voter from pushing in more than a cer-

tain number of the candidate keys, comprises a series of wedge-block separators controlled by the keys and grouping mechanism. Each of the candidate group sections or units is provided with a series of wedge-blocks 72 (see Fig. 2) which slide upon the bottom of the section in contact with the rear wall thereof. Each section has one more wedge-block than it has keys and the wedge-blocks are cut away at their forward, adjacent edges to form spaces 73 which receive the separator pins 74. These separators are connected by links 75 to pins 57, extending through the slides 46 in rear of the keys 45. The cut-away portions of the blocks forming the spaces 73, are beveled or inclined at their rear ends so that the separators 74, whenever the corresponding key is actuated, will be forced between the adjacent blocks to elongate the series of blocks. The connecting links 75 permit the movement of the blocks and separators 74 transversely of the keys without changing the relation between the separators and wedge-blocks. Obviously it is only necessary to limit the movement of the first and last blocks of any series of blocks in one or more of the candidate group sections to limit the number of keys which can be actuated. If the movement of the series of blocks is limited to one step, *i. e.* to the diameter of one of the separators 74, one key only can be pushed in. If it is limited to two steps, two keys can be pushed in and so on. In the arrangement shown, the center block of the series in each unit or section is fixed in position by pins or studs 77, (see Fig. 2). One end block is provided with a lug 78 which engages a notch in the end of a sliding bar 79. Bar 79 slides upon the bottom of the section between the front edges of the blocks 72 and the rear edge of the actuator rack-bar 31. The block at the other end of the section is pivoted to the center of a horizontal link 80, which is slotted at its forward end to engage a pin 80' on the end of bar 79. The rear end of the link 80 projects through a slot in the rear wall of the section and is connected to the means by which the movement of the blocks is limited. If one or more of the separators to the left of the center fixed wedge-block are pushed in, the bar 79 will move the link 80 one or more steps in accordance with the number of separators so operated. If the separators at the right of the fixed block are pushed in, the right hand end block will move the link 80 one or more steps in accordance with the number of separators pushed in, and it would move the link in the same direction as the latter is moved by the bar 79. By this arrangement the extent of movement of the individual blocks and separators transversely to the keys, is considerably cut down.

For example, in Fig. 2 four separators are shown and if all are pushed in, the link 80 will be moved four steps, but no one block will have moved more than two steps. By reason of this arrangement, the links or arrows 75 which connect the separators with the keys and which compensate for the transverse movement of the separators relatively to the keys, can be much shorter than they would have to be if one of the blocks of the series moved as many steps as there were separators when all of the separators were pushed in. It will of course be understood, that unless the section is arranged in a multicandidate group, the movement of link 80 is limited to one step so that this arrangement is only of particular advantage when the section or unit is to be arranged in a multicandidate group. But it is important that all of the sections should be so connected that they can be placed or assembled with other of the units in a multicandidate group, as may be desired.

Each link 80 is connected to one of the limiting bars 81 of the grouping mechanism, preferably by means of an adjustable connection comprising a link 82 which is pivoted to the rear end of the link 80 and which is provided with a slot arranged to receive a pin 83 connected to the ends of the sections of the limiting bar 81. An adjusting screw 84 extends longitudinally through the link 82 and engages the cross-pin 83. Each bar 81 is as stated, preferably formed of separate sections which extend across the rear face of the machine and on opposite sides of a guide frame 85 see Fig. 3, secured to, but spaced from the rear face of the machine. This guide frame comprises the horizontal bars 85 through which the supporting screws 86 extend, and the pairs of vertical bars 87 secured to the ends of the horizontal bars 85. Between the bars 85 are arranged the space or guide bars 88, which are narrower than the vertical bars 87 so that guide slots are formed to receive the overlapping limiting plates 89. These limiting plates are triangular in outline as shown, and are provided with squared ends which abut snugly against the guide bars 88 and the plates can therefore only shift in a vertical direction within the guide frame. Removable pins 90 extend through the bars 87 and limiting plates 89 and hold them in the position shown in Fig. 3. The sections of each of the limiting bars 81 are connected by a cross-pin 91 which extends between two of the limiting plates and engages the inclined edge of the lowermost limiting plate.

The machine is provided with one more of the limiting plates 89 than it has candidate group sections, so that the pin 91 on each of the several limiting bars 81 which correspond in number to the candidate

group sections, coöperates with two of the limiting plates. If the plates 89 on opposite sides of any one of the pins 91 are fixed in position, that pin will be arrested by engaging the lower edge of the plate above it when the space blocks and limiting bar 81 of the corresponding unit or section, have been moved one step. When any of the candidate group sections or units are to be used for a single office, that is to represent an office to which but one candidate may be elected, the plates on the opposite sides of the end of the corresponding limiting bars 81, are fixed in position. By properly adjusting the connection between the bar 81 and the link 82, the movement then permitted can be nicely regulated to a single step so that but one of the several keys and separators of the unit or section can be pushed in, and but one vote recorded for the office represented by the section. But it often occurs that there are offices to which there are several persons to be elected, and such conditions necessitate multicandidate groups. That is, several of the office rows or units must be coupled together to permit a voter to cast all of his ballots for the candidates named in a single row, or to vote the straight ticket or otherwise cast his vote. For this purpose, any of the limiting plates 89 may be unlocked by removing the pins 90. If the top and bottom plates alone are held in position while the intermediate plates are unlocked, the whole machine will be thrown into a multicandidate group and the voter may push in as many keys as there are office units or office rows, and he may bunch all of his votes in a single row, vote a straight ticket or cut up his ballot in any desired manner. Usually however, it is not necessary to use the whole machine as a multicandidate group. Most of the units ordinarily will represent but a single office and the limiting plates on either side of the bars 81 corresponding to the single office groups, will be locked in place by the pins 90. Where a few adjacent units or sections are thrown into a multicandidate group, the limiting plate below the bar 81 of the lowermost section of the group and the plate above the bar 81 of the uppermost section of the group, will be locked while the intermediate plates are left free. The voter may then push in as many keys in the multicandidate group as there are sections or office rows thus arranged in the group, and these votes may be distributed within the multicandidate group in any desired manner.

To prevent interference with the limiting and grouping mechanism and other parts on the rear face of the machine, these parts are inclosed in a casing 6 carried at its upper edge on pins 93 and secured in place at its lower edge by a lock 94, so that only the city clerk or other proper official having the

key to the lock 94, can have access to the limiting mechanism for properly adjusting or setting the same prior to an election.

The sections of the limiting bars 81 extend on opposite sides of a pair of vertically disposed parallel movement bars 95 and 96. These bars are pivotally connected at their ends to links or bell levers 97 and 98. These links are carried intermediate their ends on pivots 99 and 100, which are mounted respectively in the sections 3 and 4 of the machine. The link 98 is fixed to the pivot 100 and the rear end of the latter is arranged opposite an opening in the cover-plate 6 and has a squared portion adapted to receive a suitable key by which the judge of election may shift the bars 95 and 96. Bar 96 is arranged to engage and coöperate with a series of pins 101 extending between the sections of the limiting bars 81 to lock the bars and space-blocks connected thereto against movement with the bar 96 in the position shown in dotted lines in Fig. 3, and with all of the pins 101 in place, none of the voting keys can be pushed in. When special class electors are to vote for certain offices, the pins 101 of the limiting bars 81, connected to the sections or units representing these offices, are removed. When a special class voter is to cast a ballot, the judge of election will shift the class-bar 96 into position shown in dotted lines in Fig. 3, and this will lock all of the keys of the machine except those representing the offices to which the special class elector is entitled to cast a ballot. The bar 96 is cut away or notched at its upper end so that the pivots at its ends may be brought in line above the pivots 99 and 100, and the weight of bar 95 will securely hold the bar 96 in this normal position, shown in full lines in Fig. 3 so that there is no danger that it will be accidentally shifted to lock the machine.

Means are provided for controlling the casting of free ballots for irregular candidates whose names are not on the machine. Such means consists of devices by which a free ballot may be so marked as to indicate the offices for which the elector has a right to cast a free ballot. That is to say, the free ballot is so marked as to identify those offices for which the voter has not cast a ballot for one of the regular candidates whose names appear upon the face of the machine. These devices are so connected to the limiting mechanism that this object is attained. Preferably, printers bearing identifying numerals, names or other marks corresponding to the several offices are employed. These printers are actuated by suitable keys and their operation is controlled by the locking and limiting mechanisms.

Each of the sections or units is provided at its end with a plate 103 which is riveted thereto and which is provided on its inner

- face with a cut-away space 104 and on its outer face with a clip 105. The plates 103 are of the same width as the separate sections of the machine and when the sections 5 are set one upon the other, the cut-away spaces 104 form a continuous slot which receives a holder 106. This holder is provided on its upper end with an out-turned clip 107, which supports the holder in place.
- 10 A plate 108 having prongs on its upper edge, is secured to the inner face of the holder 106, and the wires 109 secured to and depending from the holder, are provided on its lower ends with prongs. An inking ribbon 110 is stretched between the prongs of the plate 108 and the prongs on the lower ends of the wires 109 are so held in place within the cut-away spaces 104. The free ballot is placed by the voter within the clip 15 105 and each section or unit is provided with a printing plunger or head 111 arranged to shift through openings 112 in the end of the section and in the plate 103, and thus force the inking ribbon 110 against 20 the free ballot to impress the identifying number or other mark upon the free ballot. Each of the printing heads bears its own particular identifying number, name or other mark which corresponds to the candidate 25 represented by the unit or section in which the plunger is mounted. The plunger is carried in a block 113 arranged between a pair of plates 114 which are secured to the bottom of the section in front of the 30 end of the actuator-bar 31. The front edge of the actuator-bar 31 engages the rear plate 114 so that the end of the bar is guided by the plate.
- The counter at the extreme right hand 35 end of the section registers the number of times that the free ballot printer is operated, and is in all respects similar to the counting mechanism previously described, except that a rocking-key 115 (see Fig. 4) is employed instead of a push key. This rocking key is mounted upon the cross-pin 42 and is arranged to operate the cam 60 thereon to move the slide 46, actuator 47 and separator 74 connected thereto. The cam 40 and pin in the other counting mechanism are connected to the straight ticket bars which are not employed in the free ballot mechanism. The pin 45', which carries the actuator 47 of the free ballot register, does 45 not extend through the front of the casing to form a push key as in the other counting mechanisms.
- The pin or rock shaft 42 of the free ballot mechanism carries an actuating shifter for 50 the printer in the form of a cylindrical piece 116 (see Figs. 4, 5 and 6), having a slot 117 in one side and a projecting V-shaped piece 117' which in normal position engages the bottom of the section or unit and limits the 55 movement of the printer actuator in one di-
- rection. A slide 118 shifting longitudinally between the plates 114, carries a cross-pin 119 upon which is mounted an arm 120. One end of the arm is connected by a pair of links 121 to the end of the reciprocating printer head 111 and the other end extends within the slot 117 of the shifter 116 above an abutment 122 at the lower end of the slot. The sliding block 118 carries a pin 123, to which is pivoted a bell-crank 124. One arm of the bell-crank is slotted at its end to engage a pin 125 on the end of the restoring-bar 32. The other arm of the bell-lever 124 is provided with a cam-shaped slot 126, which engages a pin 127 on a plate 128, which is secured in fixed position to the plates 114. The cross-pin 119, which carries the shifter 120 in the slide 118, projects through guide slots 129 in the sides of the plates 114 (see Fig. 6). The shifter 120 is provided on its lower edge with a lug 130 which is arranged to engage a fixed cross-pin 131 extending between the plates 114.
- As the elector enters the booth, the locking or restoring bar 32 is shifted to the left, as described, to release the slides and keys of the several registering mechanisms including that belonging to the free ballot devices. At the same time the bell-lever 124 is shifted about its pivot. During this shift the cam-slot 126 of the bell-lever co-operates with the fixed pin 127 to move the pivot pin 123, slide 118 and arm 120 toward the right or toward the printing head 111 as shown in Figs. 4 and 5. If the elector desires to cast a ballot for an irregular candidate for any office, he will operate the free ballot key corresponding to that office. This will turn the shifter 116 toward the left and the engagement of the abutment 122 thereon with the end of the arm 120 will project the printing head 111 and the free ballot within the clips 105 will be thus printed with an identifying mark representing the office for which the elector has a right to vote. The operation of course shifts the separator connected to the free ballot mechanism between the wedge-blocks of the limiting mechanism so that the elector cannot cast another vote for the same office by operating any of the regular keys. Of course, the free ballot mechanism may be arranged in a multi-candidate group and then the elector may cast as many ballots either regular or irregular, as there are office rows or sections arranged in the group. When in multicandidate group the ballots which are to be marked by the printing mechanism should be of a size sufficient to fit within the clips 105 connected to all of the units or sections in the group. Where the sections represent single candidates only small clips may be employed. After the free ballots have thus been printed with an identifying number or 130

other mark, the elector may write thereon the name of the irregular candidate for whom he desires to cast a ballot and the ballot is then placed within a suitable box.

5 It will be understood of course, that no free ballots will be counted unless they have been properly marked with the printing mechanism.

As the printer is operated by the engagement of the abutment 122 with the tail of the arm 120, the toggle formed by the shifter 120 and the links 121 is moved past its line of centers and the movement of the shifter 116 is arrested by the engagement of the abutment 117 thereon with the lower edge of the arm 120. By this movement of the parts 120 and 121 past their line of centers, the printing head is projected and then withdrawn. It is obvious however, 10 that it cannot again be operated by any further manipulation of the key 115 or actuator 116. As the operator leaves the booth, the restoring bar 32 is shifted toward the right and bell-lever 124 is swung back about the pin 123 so that the cam 126 and pin 127 coöperate to move the slide and shifter back toward the left. This movement brings the lug 130 on the shifter into engagement with the fixed pin 131 so that 15 the shifter is turned from its lowermost position into which it has been moved by the shifter 116 back to its uppermost normal position shown in Fig. 5. During this restoring movement of the shifter, the 20 printing head 111 is of course projected toward the right and withdrawn, but it is not projected far enough to again mark a ballot, since, during this restoring movement, the pivot 119 of the shifter is at the 25 inner end of the slot 129 and the slide 118 and arm 120 are drawn away from the right hand end of the section or unit. The parts 30 are so arranged that it is only when the pin 119 and shifter 120 are in their extreme, 35 outermost position that the printing head will be projected far enough by the shift of the toggle members 120 and 121 past the line of centers to mark the ballot.

What I claim as my invention is—

50 1. In voting machines, the combination with the series of counters, the series of limiting blocks therefor and separators coöperating with said blocks, of connections between the end blocks of the series, one of 55 the intermediate blocks being held against movement.

2. In voting machines, the combination with the office group of registering devices, of a series of limiting blocks and separators 60 coöperating therewith and a connecting link between the end blocks of the series, one of the intermediate blocks being fixed in position.

3. In voting machines, the combination 65 with the office group of voting mechanisms

and with the series of limiting blocks and separators therefor, one of the intermediate blocks being fixed in position, of an arm pivoted to one of the end blocks of the series, a bar connecting said arm with the 70 other end block of the series and means for limiting the movement of said arm.

4. In voting machines, the combination with the office groups of counters, limiting blocks and separators therefor, of a set of 75 limiting blocks connected to the groups of blocks by bars, a set of devices for limiting the movement of said bars and means for releasably holding said limiting devices in position.

5. In voting machines, the combination with the office groups of counters and limiting mechanisms for each group, of a set of bars connected to the limiting mechanisms of the several groups, a set of overlapping 85 limiting plates coöperating with said bars and means for removably holding said plates in position.

6. In voting machines, the combination with the office groups of counters and limiting mechanisms for each group, of a set of 90 bars connected to the limiting mechanisms of the several groups, a series of overlapping sliding plates coöperating with said bars to limit the movement thereof, and removable pins for holding said plates in position.

7. In voting machines, the combination with the office groups of counters and limiting mechanisms for each group, of a set of 100 bars connected to the limiting mechanisms of the several groups, a series of overlapping sliding plates each having one inclined edge and one straight edge, pins on the ends of said bars between the inclined 105 edge of one plate and the straight edge of the next adjacent plate and removable means for holding said plates in position.

8. In voting machines, the combination with the office groups of voting mechanisms 110 and with the limiting blocks and separators therefor, of a set of limiting bars, adjustable connections between said bars and the separate groups of limiting blocks, a series of overlapping sliding plates, a frame 115 wherein said plates are mounted, pins on said bars engaging said plates and removable means for holding said plates in position.

9. In voting machines, the combination 120 with the office groups of voting devices and limiting mechanism therefor, of a frame fixed to the machine casing, a series of overlapping sliding plates carried in said frame, releasable means for holding said plates in 125 position, a set of limiting bars each comprising two sections extending on opposite sides of said frame, pins extending between the sections of said bars and between the plates in said frame, and connections between the 130

opposite ends of said bars and the limiting mechanism of the several groups of voting devices.

10. In voting machines, the combination with the office groups of voting devices, of limiting mechanism for each of said groups comprising a series of blocks, the central one of which is fixed in position, an arm pivoted to one of the end blocks of the series, a link connecting said arm with the other end block of the series, a series of limiting bars connected to said arms, a set of overlapping sliding plates coöperating with said bars to limit the movement thereof and releasable means for holding said plates in position.

11. In voting machines, the combination with a series of unit frames or sections connected to form the frame of the machine, of an office group of voting mechanisms mounted in each of said frames, limiting mechanism in each of said unit frames, a set of limiting bars arranged outside of said frames and connected to the separate limiting mechanisms thereof, of a set of devices coöperating with said bars to limit the movement thereof, a casing arranged over said limiting bars and devices and a lock for holding said casing in position.

30 12. In voting machines, the combination with the office groups of voting devices and with limiting mechanisms therefor, of a set of bars connected to said limiting mechanisms, means for limiting the movement of said bars, a series of removable pins on said bars arranged in line, and a parallel movement bar shiftable into and out of engagement with said pins.

40 13. In voting machines, the combination with the office groups of voting devices and with the limiting mechanisms therefor, of a parallel movement bar, a series of bars connected to said limiting mechanisms, each comprising separate sections extending on opposite sides of said parallel movement bar, means for limiting the movement of said set of bars and a series of removable pins connecting the sections of said bars and coöperating with said parallel movement bar to lock out certain of the office groups of voting devices.

45 14. In voting machines, the combination with the office group of voting devices and limiting mechanism therefor, of a printer in said group for marking independent ballots with an identification character corresponding to the group and a key-actuated shifter capable of operating said printer once only for each operation of the machine, said shifter being connected to the limiting mechanism.

55 15. In voting machines, the combination with the office group of voting devices and limiting mechanism therefor, of a printing head or plunger associated with said group

of voting devices and a key-actuated shifter arranged to advance and retract said printing plunger, said shifter being capable of operating said plunger once only for each operation of the machine.

16. In voting machines, the combination with the office group of voting devices and limiting mechanism therefor, of a reciprocating printing head or plunger associated with said group of voting devices, a key-actuated shifter arranged to advance and retract said printing plunger, said shifter being capable of operating said plunger once only for each operation of the machine and means for restoring the operative relation between said shifter and said plunger.

17. In voting machines, the combination with the office group of voting devices and limiting mechanism therefor of a reciprocating printing head or plunger associated with said group of voting devices, a key-controlled shifter operable once only for each operation of the machine to advance and retract said printer, a holder for the free ballot, a shifting bar arranged to advance and retract said printer to and from said holder and to restore the same into operative relation with said shifter.

18. In voting machines, the combination with the office group of voting devices and with the limiting mechanism therefor, of a reciprocating printing head or plunger associated with said group of voting devices for marking independent ballots, a holder for the independent ballot, a key-controlled shifter operable once only for each operation of the machine to advance and retract said printing head or plunger, a movable device for advancing or retracting said printing head or plunger to and from said holder as the voter advances and retreats from the machine and for restoring said printer into operative relation with said shifter, and connections between said key-controlled shifter and the limiting mechanism.

19. In voting machines, the combination with the office group of voting devices and with the limiting mechanism therefor, of a shifting printer for marking independent ballots, a pivoted arm connected to said printer and a shifter engaging said arm to move it past its central position and advance and retract said printer.

20. In voting machines, the combination with the office group of voting devices, and the limiting mechanism therefor, of a shifting printing head or plunger associated with said group of voting devices, a pivoted arm, a link connecting said arm to said plunger, a shifter arranged to engage said arm to move the same past its central position and advance and retract said printing head or plunger and means for restoring

said arm into operative relation with said shifter.

21. In voting machines, the combination with the office group of voting devices, and the limiting mechanism therefor, of a shifting printing head or plunger associated with said group of voting devices, a pivoted arm, a link connecting said arm to said plunger, a shifter arranged to engage said arm to move the same past its central position and advance and retract said printing head or plunger, a holder for the independent ballot and means for advancing and retracting said plunger to and from said holder as the voter advances to and retreats from the machine, said means being also arranged to restore said arm into operative relation with said shifter.

22. In voting machines, the combination with the office group of voting devices and the limiting mechanism therefor, of a reciprocating head or plunger for marking independent ballots associated with said group of voting devices, a shifting slide, an arm pivoted on said slide, a link connecting said arm with said printing head or plunger, a shifter arranged to engage said arm to move the same past its central position and advance and retract said plunger and means for moving said slide to restore said arm into operative relation with said shifter.

23. In voting machines, the combination with the office group of voting devices and the limiting mechanism therefor, of a reciprocating printing head or plunger for marking independent ballots associated with said group of voting devices, a shifting slide, an arm pivoted on said slide, a link connecting said arm with said printing head or plunger, a shifter arranged to engage said

arm to move the same past its central position and advance and retract said plunger, means for moving said slide and a fixed stop arranged to engage said arm as it is shifted with said slide and restore it into operative relation with said shifter. 45

24. In voting machines, the combination with the office group of voting devices and the limiting mechanism therefor, of a reciprocating printing head or plunger for marking independent ballots associated with said group of voting devices, a shifting slide, an arm pivoted on said slide, a link connecting said arm with said printing head or plunger, a shifter arranged to engage said arm to move the same past its central position and advance and retract said plunger, a holder for the independent ballot, means for shifting said slide to and from said holder as the voter advances to and retreats from the machine and a fixed stop arranged to engage said arm as it is moved with said slide to restore the arm into operative relation with said shifter. 55 60

25. In voting machines, the combination with a series of unit frames fitted together, of an office group of voting mechanisms carried by each frame, a printing head for marking independent ballots associated with each group of voting mechanisms, plates 70 fixed to the ends of said frames having cut-away spaces forming a continuous slot, a ribbon holder arranged within said slot and clips fixed to said plates for holding the independent ballot.
